UNITED STATES PATENT OFFICE

ANDREW McC. GARDNER, OF NASHVILLE, TENNESSEE, ASSIGNOR OF ONE-HALF TO
BENJAMIN C. WOODWARD, OF NASHVILLE, TENNESSEE.

BELT-BUCKLE.

941,242.

Specification of Letters Patent. Patented Nov. 23, 1909.

Application filed May 22, 1909. Serial No. 497,629.

To all whom it may concern:

Be it known that I, ANDREW McC. GARDNER, citizen of the United States, residing at Nashville, in the county of Davidson and State of Tennessee, have invented certain new and useful Improvements in Belt-Buckles, of which the following is a specification.

This invention relates to buckles, and particularly to those used for attaching the ends of belts.

The object of the invention is to form an improved device for the purpose stated characterized particularly by novel means for holding the ends of the belt and for permitting adjustment thereof to vary the size of the belt.

The invention is illustrated in the accompanying drawings in which—

Figure 1 is a front view thereof; Fig. 2 is a rear view of the buckle, the belt being removed; Fig. 3 is a top edge view of the buckle; Fig. 4 is a section on the line 4—4 of Fig. 1; Fig. 5 is a top edge view of the buckle in open position.

Referring specifically to the drawings, 6 indicates a front plate adapted to conceal the remainder of the buckle, and which may be ornamented or decorated as desired, and 30 which is the only part of the device which shows when it is in use. The belt is indicated at 7. On the back of said plate, near one end thereof, is affixed a hinge member 8 which is provided for a portion of its length 35 with a row of teeth 9 presented inwardly, or toward the other end of the plate. The member 8 receives, for pivotal connection, the ends of a vertically elongated loop 10 the opposite side of which is covered or 40 faced with a sheet metal plate 11. The loop 10 is preferably made of stout wire or the like, and the wires are extended horizontally across the buckle forming a bar 12 composed of two strands of the wire which are 45 bent at the opposite end to form a vertically elongated loop 13 which is substantially a duplicate of the loop 10. The loop 13 is also provided on its inner side with a sheet metal plate 14 and on its outer or distant 50 side with a hinged clamp member 15 which is arranged to turn on the loop and which has a row of teeth 16 projecting toward the edge of the plate 13 when the buckle is closed. The plate 6 also has a rearwardly 55 projecting snap clasp 17 consisting of a

plate or piece of spring metal soldered or otherwise fixed to the back of the plate, with a projecting lip turned up to proper position so that the member 15 when pressed against the front plate will snap in behind the lip 60 and be held in closed position against the front plate.

The hinge connection between the part 8 and the loop 10 allows the whole back frame of the buckle to be swung open, or 65 rather allows the front plate to be swung away from the belt-holding members of the buckle to allow access to the ends of the belt for the purpose of adjusting or manipulating the same. One end of the belt 7 is inserted through the loop 13, the plate 6 being swung open or away and the clamping member 15 being turned to open position, as shown in Fig. 5. When the member 15 is turned or pressed in the toothed part 16 70 thereof engages the end of the belt which is thereby clamped in the loop 13 against the bend or knuckle of the plate 14 on the opposite side of the loop, the teeth engaging the belt to hold the same. The front or guard 75 plate 6 is then swung to closed position, the end 7^a of the belt inserted through the loop 10 and then being first pulled to snug or tight position to fit the waist of the person using the belt. When the plate 6 is swung 80 to closed position the teeth 9 of the member 8 engage said belt and clamp the same against the knuckle of the plate 11 on the opposite side of the loop 10 thereby fastening the said end in the loop and holding the 85 belt; and when the plate 6 is pressed to fully closed position the knuckle of the member 15 snaps in under the lip of the catch 17, thereby holding the front plate in closed position and locking the clamping members 90 which hold the ends of the belt. To unfasten the belt it is simply necessary to pull open the front plate 6, disengaging the same 95 from the remainder of the buckle at the lip 17. This action opens the belt clamp at the loop 10 and allows the end 7^a of the belt to be pulled out or detached, thereby permitting removal of the belt. The opposite end 100 of the belt, being the end engaged by the clamp 15, will as a rule remain fixed, although it may be adjusted by opening the buckle and turning the part 15 outwardly as shown in Fig. 5, which will release the belt at that end. The clamping devices provided 105 are without objectionable penetrating 110

tongues and permit the belt to be adjusted to any necessary position. A different belt can be readily substituted without removing stitches or the like, by merely unfastening 5 both ends of the belt from the respective clamps which hold the same.

Although illustrated and described in connection with a belt, the device is applicable to garters, bends etc., and no limitation is 10 implied with respect to use.

I claim:

1. The combination of a front plate, and a buckle member hinged to said plate, to swing to and from the same, means to hold said 15 member in closed position against the plate, a clasp for one end of a belt, said clasp having separate parts attached respectively to the plate and said member and arranged to hold the end of the belt when the member is 20 closed against the plate, and a clasp carried by said member for the other end of the belt.

2. The combination of a front plate, a hinge member fixed to the back thereof near one end and having a projecting edge, a

frame provided with loops at opposite ends 25 to receive the ends of a belt or the like, one loop being pivotally connected to said member and arranged to swing to closed position and to thereby clamp the belt end against said edge, a pivoted clasp member mounted 30 on the other loop and constructed to grip the end of the belt therein, and means to hold the frame closed against the front plate.

3. The combination of a front plate having a spring clip on the back thereof, a 35 buckle frame hinged at one end to the back of the plate and having clasps at opposite ends to engage the ends of a belt or the like, the clasp at the free end having a turning clamping part which is engaged and held 40 closed by the clip when the frame is swung to closed position against the plate.

In testimony whereof, I affix my signature in presence of two witnesses.

ANDREW McC. GARDNER.
